DEFENSIVE PUBLICATION

UNITED STATES PATENT AND TRADEMARK OFFICE

Published at the request of the applicant or owner in accordance with the Notice of Dec. 10, 1960, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

19 Sheets Drawing, 50 Pages Specification

INVENTOR'S STATEMENT
Method and apparatus for incorporating user-added data base, report specification, and calculation program information into programs for a computer that are customized in accordance with responses to a questionnaire. User-added program information is especially identified and supplied together with the responses to the questionnaire for verification. The responses are checked in accordance with verification instruction, none of which are directed to the especially identified program information. The verified responses are employed to select and modify customizing instructions which, in turn, delete, select, and modify program statements. The especially identified program information together with certain of the program statements are sorted into a sequential arrangement and are checked for consistency and for agreement with any prior stored information. The program information and selected program statements are then sorted into final output format and supplied as final output.
